UNITED STATES PATENT OFFICE

128,128

DESIGN FOR A GUITAR PLAYING BAR

Victor F. Zepp, Chicago, Ill., assignor to Allen Sechler, Chicago, Ill.

Application April 23, 1941, Serial No. 100,587

Term of patent 3½ years

To all whom it may concern:

Be it known that I, Victor F. Zepp, a citizen of the United States, residing at Chicago, in the county of Cook and State of Illinois, have invented a new, original, and ornamental Design for a Guitar Playing Bar, of which the following is a specification, reference being had to the accompanying drawing, forming part thereof.

I claim:

The ornamental design for a guitar playing bar, as shown.

VICTOR F. ZEPP.
